ATTORNEYS

UNITED STATES PATENT OFFICE.

RUSSELL WHITCOMB, OF ELIZABETH, AND GEORGE H. HARMAN, OF GLEN RIDGE, NEW JERSEY.

POWDER-PUFF.

1,376,179.

Specification of Letters Patent. Patented Apr. 26, 1921.

Application filed June 28, 1920. Serial No. 392,296.

To all whom it may concern:

Be it known that we, RUSSELL WHITCOMB, a citizen of the United States, residing at Elizabeth, county of Union, and State of New Jersey, and GEORGE H. HARMAN, a citizen of the United States, residing at Glen Ridge in the county of Essex and State of New Jersey, have invented certain new and useful Improvements in Powder-Puffs; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in powder-puffs for applying face powders and cosmetics to the skin of the user; and, the said invention has reference, more particularly, to a novel construction of powder-puff comprised of few parts which may be easily and quickly assembled together to provide a very cheap, durable, and simple puff of attractive appearance.

The invention has for its principal object to provide a novel powder-puff construction requiring a minimum number of parts, which, by simple operations, may be easily and quickly assembled together, whereby the wool or velour facing of the puff is firmly secured and stretched without necessity of employing hand or machine stitching, stapling or other fastening means or methods, other than the gripping and holding effect upon wool or velour facing provided by the novel construction of supporting form and coöperating back member.

Another object of the present invention is to provide a novel construction of supporting form and coöperating back adapted when assembled in normal relation to the wool or velour facing material to hold the latter properly stretched and formed without necessity of providing internal stuffing or padding material, and at the same time so shaping and holding said facing that no sharp corners or edges of any kind are presented by the facing of the puff or the supporting member thereof, which are likely to scratch or otherwise injure the skin of the user.

Other objects of the present invention,

not at this time more particularly enumerated, will be clearly understood from the following detailed description of the same.

With the various objects of the invention in view, the same consists, primarily, in the novel construction of powder-puff herein-after set forth; and, the invention consists, furthermore, in the novel arrangements and combinations of the various devices and parts, as well as in the details of the construction of said parts, all of which will be more fully described in the following specification, and then finally embodied in the claims appended hereto.

The invention is clearly illustrated in the accompanying drawings, in which:—

Figure 1 is a back view of the novel construction of powder-puff made according to and embodying the principles of the present invention; Fig. 2 is a face view of the same; Fig. 3 is a side or edge view of the same; Fig. 4 is a central vertical transverse section of the same; and Fig. 5 is a side elevation of the several parts of the powder-puff construction, as arranged preparatory to assembling the same together in operative association, said view being drawn on an enlarged scale.

Similar characters of reference are employed in all of the above described views, to indicate corresponding parts.

Referring now to said drawings, the reference-character 1 indicates the complete powder-puff made according to and embodying the principles of the present invention, the same comprising an annular supporting form or member 2, preferably constructed of thin metal suitably wrought into the novel shape and arrangement, whereby the upper edge of the same is inwardly curved or curled to provide a gripping bead or member 3. The main body of said supporting form or member 2 is formed to present, at its exterior side, a downwardly and inwardly curved face 4, while the lower edge of said body is upwardly curved or curled to provide a rounded rim member 5 bounding the lower margin of the central opening of said supporting form or member 2.

The reference-character 6 indicates a disk-like backing member, also preferably constructed of thin metal, the circumferential marginal portions of which are downwardly and inwardly curved, to provide an annular

- curved seat or receiving socket 7, from the lower free edge of which extends an inwardly and downwardly inclined marginal lip 8. The main body of said disk-like backing member 6 is provided with a centrally disposed upwardly struck loop-portion 9 for holding a ring-like finger-piece 10, or other similar means for grasping the powder-puff when using the same.
- 10 The reference-character 11 indicates the facing material providing the powder carrying element of the puff. This facing material is preferably made of a suitable wool material, such as a fleece-surfaced fabric or a velour material.
- 15 In assembling the various elements of the powder-puff, constructed as above described, a circular piece of said facing material 11, is placed to extend across the under side of said supporting form or member 2, whereupon the marginal portions 12 (see Fig. 5) are turned upwardly and over the curved face 4 of said supporting form or member 2, so that the free edges extend inwardly 20 above the gripping bead or member 3. When the facing material 11 is thus positioned the backing member 6 is registered with the upper opening of the supporting form or member 2 which is bounded by said 25 gripping bead or member 3. When thus positioned, the backing member 6 is pressed downwardly, so that said lower marginal lip 8 in entering said upper opening of the supporting form or member 2 engages the 30 edges of the material 11, and thrusts the same downwardly around the gripping bead or member 3, at the same time thus causing the material 11 to be tautly stretched over and around the supporting form or member 35 2. Continued downward pressure exerted upon said backing member will then cause the gripping bead or member 3 to spring into the annular curved seat or receiving socket 7 thus firmly gripping and holding 40 the material of the facing firmly clamped between said receiving socket and said gripping bead or member 3, and the several parts thereby firmly interlocked together in operative assembled relation to provide the completed powder-puff ready for service.

It will thus be understood from the above description, and from an inspection of the accompanying drawings, that the present invention provides a very simple and easily 45 assembled construction of face powder-puff, which in its completed form is of very neat and attractive appearance. The facing material 11 being stretched over the open annular supporting form or member 2, has all the 50 appearance of a generously padded puff, without requiring the use of stuffing or padding material necessitating considerable expense of time and labor in assembling.

Furthermore, since the operative face or 55 portion of the facing material 11, is tautly

stretched over a central opening of the supporting form or member 2, the said operative face is thus rendered more or less resili- 70 ent, so as to provide a soft contact with the face of the user and at the same time being readily capable of conforming itself to the surface of the user's features at points thereof to which the puff is applied.

We are aware that some changes may be made in the arrangements and combinations 75 of the various devices and parts, as well as in the details of the construction of the same, without departing from the scope of our present invention as set forth in the foregoing specification and as defined in 80 the appended claims. Hence, we do not limit our invention to the exact arrangements and combinations of the various devices and parts as described in said specifications, nor do we confine ourselves to the 85 exact details of the construction of the said parts as illustrated in the accompanying drawings.

We claim:—

1. In a device of the kind described, an 90 annular supporting form having an inwardly projecting gripping bead at its upper edge, a backing member provided at its periphery with an integral depending skirt having an annular receiving socket formed 95 therein, a facing member, said facing member extending across the lower side of said supporting form with its marginal portions folded upwardly around said supporting form and inwardly over said gripping bead, 100 and said backing member having the receiving socket of said skirt sprung over said gripping bead to clamp said marginal portions of the facing member between said gripping bead and said skirt.

2. In a device of the kind described, an annular supporting form presenting a downwardly and inwardly curved external face, an integral inwardly projecting gripping bead at the upper edge of said supporting form, a facing member extending over said supporting form with its marginal portions turned inwardly over said gripping bead, a backing member, a downwardly and inwardly inclined portion skirting the 110 periphery of said backing member and said 115 downwardly and inwardly inclined portion having an annularly indented receiving groove sprung over said gripping bead to clamp said facing member in secured relation to said supporting form.

In testimony, that we claim the invention set forth above we have hereunto set our hands this 23rd day of June, 1920.

RUSSELL WHITCOMB.
GEORGE H. HARMAN.
